(57) **CLAIM**

The ornamental design for a hardware fixture, as shown and described.

DESCRIPTION

FIG. 1 is a top perspective view of a hardware fixture showing my new design;

FIG. 2 is a top plan view thereof;

FIG. 3 is a side elevational view thereof, the opposite side being a mirror image thereof;

FIG. 4 is a bottom plan view thereof;

FIG. 5 is an end elevational view thereof, the opposite end being a mirror image thereof;

FIG. 6 is a top perspective view of the hardware fixture shown in FIG. 1, the only difference being the slightly raised upper surface of the center insert;

FIG. 7 is top plan view thereof;

FIG. 8 is a side elevational view thereof, the opposite side being a mirror image thereof;

FIG. 9 is a bottom plan view thereof; and,

FIG. 10 is an end elevational view thereof, with the opposite end being a mirror image thereof.

The broken away portion in FIGS. 1-9 has been shown to indicate indeterminate length.

1 Claim, 2 Drawing Sheets
